(57) **CLAIM**

The ornamental design for a potty training seat, as shown and described.

DESCRIPTION

FIG. 1 is a perspective view of a potty training seat, showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

All the broken lines in the drawings depict portions of the potty training seat, that form no part of the claimed design.

1 Claim, 7 Drawing Sheets
